UNITED STATES PATENT OFFICE.

WILLIAM B. MANN, OF BALTIMORE, MARYLAND.

AIR-BRAKE VALVE.

SPECIFICATION forming part of Letters Patent No. 630,377, dated August 8, 1899.

Application filed October 5, 1898. Serial No. 692,690. (No model.)

To all whom it may concern:

Be it known that I, WILLIAM B. MANN, a resident of Baltimore, Maryland, have invented a new and useful Improvement in Air-
5 Brake Valves, which improvement is fully set forth in the following specification.

My invention relates to the triple-valve mechanism for controlling the application of air-brakes on railway-cars, and more particularly to that class of triple valves designed to produce quick serial action of the brakes by serially venting the train-pipe into the brake-cylinder. Heretofore in some forms of this class of valves when the actuating-piston of the triple valve has been given its full traverse for the purpose of producing an emergency application of the brakes a part on the piston has been caused to indirectly open a valve controlling a by-passage leading from the train-pipe around the triple valve and into the brake-cylinder, whereby train-pipe air was admitted to the brake-cylinder without passing through the triple-valve chamber; but said by-pass valve thus 15 opened by the full traverse of the piston remained open till the return movement of the piston, when it (the by-pass valve) was closed by a spring. It is desirable that the by-pass valve should close as soon as the train-pipe pressure has been sufficiently reduced to cause the prompt serial action of the next triple valve in the series, and it is therefore 20 desirable that the closing movement of the by-pass valve should be automatic and independent of the movements of the triple-valve piston. It is also desirable to avoid the use of springs in the manipulation of the valve mechanism, to the end that the said mechanism may depend in all its movements upon 25 the pressure in the train-pipe.

The objects of the present invention are to simplify the construction of triple-valve structures venting the train-pipe into the brake-cylinder, to provide a by-pass valve 30 that will close automatically without regard to the return throw of the triple-valve piston, and, furthermore, to provide a by-pass valve which will remain seated or will be unseated, as may be desired, when the triple-valve piston is given its full traverse.

With these objects in view my invention consists in a triple valve of any desired construction having a valve-actuating piston, a by-passage leading from the train-pipe to the brake-cylinder, a valve interposed in said passage, and means unseating said valve when the triple-valve piston is given its emergency throw, and means automatically seating said valve regardless of the position of the triple-valve piston. 55

Further, the invention consists of a triple valve and its actuating-piston, with a by-passage connecting the train-pipe and the brake-cylinder and a valve in said passage having operative relations with the triple-valve piston, whereby the by-pass valve may be unseated or remain seated upon the full traverse of the triple-valve piston at the will of the engineer. 60

The invention also resides in certain details more fully pointed out in the claims. 70

I have illustrated one form which my invention may assume in the accompanying drawings, in which—

Figure 1 is a longitudinal section, partly 75 in elevation, showing the parts in the position they occupy when the brakes are released. Fig. 2 is a like view showing the parts in the position they assume in the emergency application of the brakes, and Fig. 3 80 is a similar view with the parts in position for service or graduating application.

Like letters refer to like parts in all the views, in which—

A indicates the valve-casing; B, the triple 85 valve; C, the triple-valve piston; D, the passage leading from the train-pipe; E, the passage to the auxiliary reservoir, and F the passage to the brake-cylinder.

G is the exhaust-port leading to the atmosphere, and H is the by-passage leading from the train-pipe to the brake-cylinder and preferably formed in the triple-valve casing A, as shown. One side of the triple-valve piston is exposed to pressure from the auxiliary 95 reservoir and the other side to train-pipe pressure in a common and well-known manner. Formed on the rear or train-pipe side of the triple-valve piston is a plunger B', which projects through an opening in the 100

rear end of the piston-cylinder. This opening is greater in diameter than the plunger B' and has formed around its margin a valve-seat I. In a rearward extension of the valve-casing A is formed a cylinder J, within which plays a piston K, having a hollow stem k, closed at its rear end, but open at its front end—that is, at the end adjacent to the plunger B', which plunger enters the hollow stem k with a loose fit. Surrounding and rigidly attached to the forward end of the hollow stem k is an annular valve k', which normally seats on the valve-seat I, thus closing the passage H from the train-pipe D to the brake-cylinder passage F. The cylinder J is at all times in free communication with the train-pipe through a passage j, formed in the valve-casing, and the interior of the hollow piston-stem k is also in communication with the train-pipe by reason of the loose fit of the plunger B' in said stem, the valve k' being normally held seated by reason of the differential pressures on the opposite sides thereof, it being of course understood that the passage H is normally in communication with the atmosphere through the exhaust-port G. Between the valve-seat I and the brake-cylinder passage F and preferably in the passage H is a spring-pressed check-valve h, opening from the direction of train-pipe pressure toward the brake-cylinder.

The operation of the device is as follows: When it is desired to produce an emergency application of the brakes, the pressure in the train-pipe is quickly lowered at the engineer's valve, thus causing the piston C to suddenly make its full traverse from the position shown in Fig. 1 to that of Fig. 2, thereby forcing the plunger B' into the hollow stem k and compressing the air contained therein to such an extent as to overcome the pressure on the rear side of piston K and unseat the valve k'. The valve k' being unseated, air from the train-pipe D enters the passage H, raising the check-valve against its light spring, and passes to the brake-cylinder passage F, and at the same time auxiliary-reservoir air enters the brake-cylinder through the passage E and the port e. I prefer to construct the port e of much smaller area than the cross-section of the passage H in order that the rush of air from the train-pipe through said passage H may not be unduly checked by back pressure due to the auxiliary-reservoir pressure. By this means I insure the quick lowering of pressure in the train-pipe, upon which quick serial action depends. As stated above, the opening or unseating of the valve k' is due to the fact that the plunger B' compresses the air in the hollow stem k to such an extent as to overcome the train-pipe pressure on the rear of piston K. Owing, however, to the loose fit of the plunger B' in the hollow stem k the air rapidly escapes from the hollow stem, whereupon the compressed air in the

cylinder J acts upon the piston K and seats the valve k', thus closing communication between the train-pipe and the brake-cylinder.

In operating the valve for ordinary service application of the brakes and for "graduating," the pressure in the train-pipe is lowered but slightly and the triple-valve piston moves slower than in emergency applications and only makes a partial traverse, the parts taking the positions shown in Fig. 3. In this case the plunger B' enters the hollow stem k so slowly and for such a short distance that the air in the stem is never compressed to a degree sufficient to unseat the valve k', but escapes from the stem past the plunger, thus maintaining equilibrium of pressure in the train-pipe and the hollow stem k. If the pressure in the train-pipe is slowly reduced, the triple-valve piston may make its full traverse without unseating the valve k', and the full power of auxiliary-reservoir pressure may thus be secured without opening the passage from the train-pipe to the brake-cylinder. This is particularly advantageous when for any reason it is desired to apply full auxiliary pressure to the brakes, but without the suddenness of action occurring in an emergency stop. Should the train break in two or a damaging leak occur in the train-pipe, the check-valve h would prevent the escape of air from the brake-cylinder and consequent release of the brakes.

Having thus described my invention, I claim as new and desire to secure by Letters Patent—

1. The combination of a triple-valve casing having ports leading to the train-pipe, the auxiliary reservoir and the brake-cylinder, a triple valve and its operating-piston working in said casing, with a by-passage connecting the train-pipe with the brake-cylinder, a differential piston-valve controlling said passage, and means operating on the emergency traverse of the triple-valve piston to augment the air-pressure on the train-pipe side of said differential piston-valve to a point beyond train-pipe pressure, substantially as described.

2. The combination of a train-pipe, an auxiliary reservoir, a brake-cylinder, a triple valve and its operating-piston, with a differential piston-valve controlling a passage leading around the triple-valve chamber from the train-pipe to the brake-cylinder, and means alternating the preponderance of air-pressure per unit of surface on the piston-valve when and only when the triple-valve piston makes its full traverse for emergency stops, substantially as described.

3. The combination of the train-pipe, auxiliary reservoir, brake-cylinder, triple valve and its operating-piston, with a passage leading from the train-pipe around the triple-valve casing to the brake-cylinder, a differential piston-valve controlling said passage

and held to its seat by train-pipe pressure, and means acting on the emergency throw of the triple-valve piston to first augment and then lower the pressure on the opening side 5 of said differential piston-valve when the pressure in the train-pipe is suddenly lowered, substantially as described.

In testimony whereof I have signed this specification in the presence of two subscribing witnesses.

WILLIAM B. MANN.
